AUTOMATIC CONTROLLING MECHANISM
FOR TAXIMETERSGrover Cleveland Coil, Dayton, Ohio, assignor, by
mesne assignments, to Central United National
Bank, Cleveland, Ohio, as trustee

Application May 9, 1932, Serial No. 610,149

9 Claims. (Cl. 235—30)

This application relates to means to automatically throw the flag shaft or controlling shaft of a taximeter when the passenger's seat is occupied. Another object of the invention is to provide means to break a circuit as soon as the controlling shaft has been operated so as not to drain the battery of the car. Another object of the invention is to provide means to lock the flag against being thrown beyond its home position unless the fare drums of the taximeter have been returned to their zero position. Other objects and advantages of the invention will appear in the detailed specification and claims.

15 In the drawings:

Fig. 1 is a diagrammatic view of the cab having a spring controlled switch in the rear seat and having an automatic taximeter mounted in the cab;

20 Fig. 2 is a front elevational view of the connecting means between the flag and the flag shaft;

Fig. 3 is a diagrammatic view of the circuit;

25 Fig. 4 is an elevational view of the control mechanism mounted on the back plate of a taximeter;

Fig. 5 is a side view, partly in cross section, through the meter, taken at right angles to the view shown in Fig. 4;

30 Fig. 6 is a perspective view of a part of the mechanism shown in Fig. 5; and

Fig. 7 is a perspective view of a lever controlling ratchet and arm.

The cab 1 is provided with a seat switch 2 consisting of a plunger 3 and spring contacts 4. The plunger 3 is moved downwardly into engagement with the contacts 4 when a passenger takes his seat. The car battery 5 is grounded at 6 and is connected by a lead 7 to one of the contacts 4. The other contact 4 is connected by a lead 8 with a magnet 9 which is mounted on the back plate 10 of the taximeter. A lead 11 extends from the magnet 9 to a spring contact 12. A cam 13 normally holds a spring contact 14 in engagement with the spring contact 12, which spring contact 14 is connected to a lead 15 which is grounded at 16. When a passenger sits on the seat and moves the plunger 3 into engagement with the contacts 4 the circuit will be completed and the magnet 9 will be energized. The spring contact 14 is provided with insulation 17 and the spring contact 12 is provided with insulation 18. The spring contacts 12 and 14 are separated by an insulation block 19.

55 The flag shaft 20 is mounted on the back plate

10 and is provided with a hub 21 in which there is a notch 22. The flag shaft 20 is provided with a disk 23 which carries a pin 24 on which is rotatably mounted a pawl 25 which has a rearwardly extending arm 26 which engages a stop pin 27 carried by a lever 28 which is normally held in the position shown in Fig. 2 by means of a spring 29. This pin 27 holds the pawl 25 out of engagement with the notch 22. The flag 30 is rotatably mounted on the flag shaft 20 and is provided with 10 a large hub 31 which overlies the disk 23. A ring 32 is secured to the back plate 10 and is provided with a cam surface 33 and an arcuate surface 34 which extends from the surface 33 for a major arc ending in the cam surface 35. The inner surface of the hub 31 forms a circular surface 36 of greater radius than the arc surface 34. The disk 23 which is secured to the flag 30 carries a square pin 37 which extends within a slot 38 of the hub 21 which is secured to the flag shaft 20. A coil spring 39 connects the disk 23 to the hub 21, thereby yieldingly connecting the flag 30 to the flag shaft 20. A spring 40 connects the pawl 25 to the arm 28. The arm 28 is provided with a nose 41, as shown in Fig. 2.

25 The flag shaft may be manually operated by the driver as in conventional taximeters. All that he has to do is to move the flag 30 in a clockwise direction as viewed in Fig. 2, whereupon the pin 37 engages the right-hand end of 30 the slot 38 and positively rotates the flag shaft 20. The hub 21 and the pin 24 on which the pawl 25 is mounted would, therefore, move as a unit and the pawl 25 would be performing no function. When, however, the nose 41 engages 35 the cam surface 35 the pawl 25 would be moved into the notch 22, which would be when the flag shaft had been moved to its 90 degree, or hired, position. If the operator then wishes to move the flag to its 180 degree position, the pin 37 will 40 continue to drive the flag shaft. If now he wished to move the flag back to its 90 degree position, the pawl 25 would engage the right-hand end of the notch 22, as viewed in Fig. 2, and remove the flag shaft back to its 90 degree position. When 45 the operator had moved the flag shaft to its 270 degree position, he could also move it back to its 180 degree or its 90 degree positions. In like manner, he can complete the rotation of the flag to its home position. In other words, the pawl 50 25 is held in engagement with the notch 22 at all times when the flag is anywhere between its 90 degree and its 360 degree positions, being held in this position by means of the stationary ring 32. As will be hereinafter described, the flag shaft 55

20 is automatically thrown to its 90 degree position when a passenger takes his seat. During this movement the flag shaft 20, as viewed in Fig. 2, would move in a clockwise direction for 90 degrees and the spring 39 would tend to move the flag 30 with it. If, however, the operator has placed a piece of wood or other obstructions in the path of the flag 30, the flag 30 would remain stationary while the flag shaft 20 would make its 90 degree rotation. The notch 22 would, therefore, move 90 degrees while the pawl 25 remained stationary. The dishonest driver would accomplish no fraud by his effort. As soon as he releases the flag 30, which he will have to do 15 in order to return the flag shaft to its home position, the spring 39 will rotate the flag 30 to its 90 degree position and from then on the flag and flag shaft will operate as heretofore described. The function of the slot 38 is to permit the rotation of the flag shaft while the flag is being held stationary; that is, when the disk 21 and slot 38 therein is rotated clockwise for 90 degrees the slot would simply travel over the pin 37 until the lower portion of the slot 38 engaged the left-hand side of the pin 37, as viewed in Fig. 2.

The automatic operation of the flag shaft 20 from its zero to its 90 degrees position when a passenger takes his seat will now be described. As heretofore related in regard to Fig. 3, the 30 magnet 9 is actuated when a passenger takes his seat. This attracts the magnet bar 47 guided on pins 42. The magnet bar 47 is connected to a bar 43 as viewed in Fig. 4. When the magnet bar 47 is moved to the right as viewed in Fig. 4, it moves the bar 43 to which it is connected, which bar carries a pin 44 connected to a bell crank lever 45 pivoted on a pin 46. A spring 48 connects the pin 46 to the bar 43 so that when the magnet 9 is not actuated the bar 43 will be moved to its left or non-actuated position. The bar 43 is provided with a downwardly extending nose 49 which overlies the upper end of a bar 50 connected by a pin 51 to the bell crank lever 45 and by a pin 52 to a lever 53 pivoted on a pin 54. The pin 54 is mounted on a long lever 55 pivoted on a stud 56, which lever 55 extends beneath the flag shaft 20 and at its lower right-hand end, as viewed in Fig. 4, is connected to a spring 57, which spring tends to pull the said lever 55 upwardly or to rotate it in a counterclockwise direction. The lever 53 is provided with a pin 58 on which is mounted a lever 59 having a rearwardly extending lug 60 which underlies the left-hand end of the lever 53 and is connected 50 to said lever by means of a spring 61. The right-hand end of the lever 59 terminates in an arm 62 which normally engages the upper end of a lever 63 pivoted on a stud 64 carried by the said lever 55. The said lever 63 is provided with a 60 downwardly extending arm 65 and an arm 66 extending to the right as viewed in Fig. 4, which arm is provided with a notch 67. Mounted on the pin 64 is a lever 68 which extends on both sides of the stud 64 and is provided with a forwardly extending flange 69 which underlies a retaining pawl 70 pivoted on a stud 71 carried by the back plate 10 of the taximeter. A spring 72 connects the retaining pawl 70 with a retaining pawl 73 which will be hereinafter described. The lever 55 carries a pin 74 on which is mounted an actuating pawl 76 which is normally urged downwardly against a pin 77 by means of a spring 75. The actuating pawl 76 is provided with a cut-away portion 78 which receives the said pin 77, which cut-away portion

terminates in a nose 79. When the actuating pawl 76 is actuated the nose 79 engages one of the ratchet teeth of a ratchet 80 mounted on a hub 81, which hub also carries ratchet teeth 82 which are engaged by the retaining pawl 70. The hub 81 is also provided with an arm 83. A coil spring 84 is connected to the hub 81 and extends around the shaft 85 on which the hub 81 is mounted and extends to the pin 77, which spring 84 tends to rotate the hub so that the 10 arm 83 will engage the stop pin 86. The arm 83 normally engages an arm 87 of a bell crank lever 88 pivoted on a stud 89, which lever 88 is normally urged in a counter-clockwise direction by means of a spring 90. The lever 88 has 15 a pawl nose 91 at its right-hand end, as shown in Fig. 4.

A housing 92 encloses a spring 93, which housing is secured to a ratchet 94. The spring 93 is secured to a pin 95 carried by the housing 92 and 20 the other end of the coil spring is connected to a pin 96 secured to a four-armed spider 97. This spring is normally under considerable tension.

The cam shaft 20 has secured thereto a ratchet 98 having teeth extending for almost 180 degrees 25 corresponding to the position of the flag shaft from its 270 degree position to its 90 degree position. These teeth are acted upon by a retaining pawl 99 mounted on a stud 100, which pawl is rotated anti-clockwise by means of a spring 101. 30 The object of this construction is to prevent the flag shaft being moved from any position between its 270 degree position and its 360 degree position reversely to its 270 degree position or after it has moved beyond its home position to prevent it being rotated to any position between zero and 270 degree position back to its home position. In other words, after the flag has been thrown to its 90 degree position it cannot be returned reversely to its home position and when it has been 40 rotated beyond its 270 degree position, it cannot be rotated reversely to its 270 degree position.

Secured to the ratchet 98 are four rollers 102 mounted on studs 103. These rollers are mounted 90 degrees apart. As shown in Fig. 4, the upper arm of the spider 97 is resting in the notch 67 of the lever 63 so that this spider 97 cannot be rotated in an anti-clockwise direction, as viewed in Fig. 4. If, however, the magnet 9 were actuated, rotating the lever 45 clockwise and elevating the lever 53 and arm 62, the lever 63 would be released and the upper arm of the spider 97 would engage the cam surface 104, rotating the lever 63 anti-clockwise and releasing the spider whereupon the spring 93 will rotate the spider 55 and ratchet 94 in an anti-clockwise direction so that the curved surface 105 of the arm of the spider 97 extending to the right would engage the lower roller 102, thereby rotating the ratchet 98 and flag shaft 20 in a clockwise direction for approximately 90 degrees.

Secured to the ratchet 98 is a plate 106 and a second plate 107. The plate 106 in the form of a circle except that it is provided with a cam 13 which, when the flag shaft is in its normal or 65 home position, engages the insulation 17 of the spring contact 14 and holds the spring contact 14 in engagement with the spring contact 12. When the flag shaft, however, is rotated somewhat beyond its vacant position the insulation 70 17 of the spring contact 14 falls into a recess 103 in the plate 106 and the contact is, therefore, broken. A pawl 110 is rotatably mounted on a pin 111 carried by the back plate 10, which pawl has an arm 112 extending to the right as shown 75

in Fig. 4. This arm is provided with a laterally extending plate 113, the lower end of which normally lies in the recess 109 of the plate 106. The plate 107 is provided with a stop lug 114. The plate 107 is in front of the plate 106 as viewed in Fig. 4 so that as the two plates 106 and 107 rotate from zero to 90 degrees the cam 13 passes beyond the insulation 17 and the spring contact 14 moves downwardly out of engagement with the spring contact 12. The upper end of the plate 113 prevents the spring contact 12 from moving downwardly. As the flag shaft rotates from its 90 degree to its 270 degree position this mechanism is not affected. When, however, the flag is being moved from its 270 degree to its 360 degree position the cam 13 will elevate the spring contact 14 but the upper end of the plate 113 will also ride up on the cam 13 and will correspondingly elevate the spring contact 12 so that these two contacts remain separated. As the plate 113 rides up on the cam 13 the pawl 110 will be rotated counter-clockwise so that the pawl nose will be in the path of movement of the stop lug 114 thereby positively stopping the flag shaft in its home position.

The upper side of the pawl 110 is provided with two upstanding arms 115 and 116 between which a lever 117 extends, which lever is mounted on a pin 118 mounted on an arm 119 mounted on the frame of the machine. The other end of the lever 117 is provided with a V-shaped extension 120 which is normally received in a notch 121 of a disk 122 secured to a shaft 123 which carries a pinion 124 which meshes with and drives a pinion 125 operatively connected with the units fare indicating wheel 126. This notch 121 is so positioned that when the fare indicating wheel is at zero, the notch will be adjacent the V-shaped extension 120 and the pawl 110 will be held so that the stop lug 114 can pass beneath it. This insures that the flag shaft will be stopped in its home position and will be held in that position until the fare indicating drums have had time to be returned to their zero position.

In operation, when the passenger sits on the seat the magnet 9 is energized which pulls the bar 43 to the right as viewed in Fig. 4 and by means of the bell crank lever 45 the bar 50 is raised which elevates the lever 53 and moves the arm 62 out of engagement with the upper end of the lever 63. The spider 97 now engages the cam surface 104 moving the lever 66 in a counter-clockwise direction. The spring 93 now rotates the spring housing 92, ratchet 94 and spider 97 in a counter-clockwise direction as viewed in Fig. 4 so that the curved surface 105 of the spider engages the lowermost of the rollers 102 rotating the flag shaft for 90 degrees and unless the flag is blocked against movement the spring 39 as shown in Fig. 2 will move the flag shaft with it. As the flag shaft rotated for 90 degrees the cam 13 passed beyond the spring contact 14 and the spring contact then moves out of engagement with the spring contact 12 breaking the circuit. As the spider 97 was rotating the upper arm of the spider 97 engaged the lever 68 elevating the flange 69 and elevating the retaining pawl 70 out of engagement with its ratchet and freeing the hub 81 so that the spring 84 rotated the arm 83 against the stop pin 86, thereby freeing the arm 87 of the lever 88 and the spring 90 moved this lever upwardly so that the pawl nose 91 engaged the ratchet 94 stopping the rotation of this ratchet. Also the arm of the spider 97 which was originally in the upright position engages the

arm 65 of the lever 63 and moves the upper end thereof to the right as viewed in Fig. 4 so as to engage it with the lower right-hand surface of the arm 62, which arm yields against the tension of the spring 61. The lever 63 is thus brought back to its normal position which is the position shown in Fig. 4. This movement of the lever 63 brings the notch 67 into such a position that it will engage the arm of the spider 97 which was originally extending to the right but which has now been rotated 90 degrees to an upright position. The spider and ratchet are thus held against being rotated beyond the 90 degree position. While the spider was being moved from its zero to its 90 degree position it has correspondingly rotated the flag shaft 20 so that the flag shaft is now in its 90 degree position, which is the position which corresponds to the hired position of the taximeter.

The housing 92, ratchet 94 and spider 97 are all mounted on a stud 127 carried by the lever 55, which will be remembered is pivoted on the stud 56 and resiliently urged upwardly by means of the spring 57. If the operator moves the flag manually from its 90 degree to its 180 degree position, the flag shaft 20 is correspondingly rotated. The roller 102 engages the curved surface 128 of the spider 97 and tends to rotate this spider but it cannot be rotated for it is held by its engagement with the notch 67 of the lever 63 which is locked against movement by the arm 62. The roller 102, therefore, cams the spider 97 downwardly and the spider carries with it the lever 55 and all of the mechanism mounted on this lever. As the lever 55 moves downwardly the ratchet 94 is brought into engagement with the pawl nose 91 of the lever 83 and as the downward movement continues, the ratchet 94 is moved anti-clockwise as viewed in Fig. 4 the distance of one tooth, thereby winding the spring 93. The retaining pawl 73 prevents retrograde movement of this ratchet 94 when the roller 102 passes beyond the curved surface 128 of the spider 97.

As the lever 55 moves downwardly as above described, the nose 79 of the actuating pawl 76 engages its ratchet on the hub 81 rotating it one tooth in an anti-clockwise direction so that each time the lever 55 moves downwardly the ratchet 94 and hub 81 are rotated in an anti-clockwise direction one tooth. This would occur when the driver manually moves the flag from its 90 degree to its 180 degree position, when he moved it from its 180 degree position to its 270 degree position and when he moved it from its 270 degree position to its 360 degree position so that the ratchet 94 and hub 81 would be actuated three teeth when the flag is moved from its 90 degree to its 360 degree position. The movement for all three teeth is sufficient to rewind the spring 93 and to move the arm 83 so as to re-engage the arm 87 of the lever 88 and move the pawl nose 91 out of engagement with the ratchet 94.

I realize that many changes may be made in the specific form of this invention shown and described by way of illustration in this application and I, therefore, reserve the right to make such changes in the specific form of the invention as shown herein as I may find to be desirable. I, therefore, claim the invention broadly except as I may limit myself by the appended claims.

Having now described my invention, I claim:

1. In a taximeter, a control shaft, a spring to rotate said shaft automatically from its home position

sition to its operative position, and means whereby when said shaft is rotated in the same direction as its initial movement, said spring will be rewound by a step by step movement.

5 2. In a taximeter, a control shaft, a spring to rotate said shaft automatically from its vacant to its operative position, and means operated by said control shaft to rewind said spring by a step by step movement.

10 3. In a taximeter, a control shaft, a spring to rotate said shaft automatically from its vacant to its operative position, means operated by said control shaft to rewind said spring by a step by step movement as the control shaft is moved from its operative position to its vacant position.

15 4. In a taximeter, a control shaft, a spring to rotate said shaft automatically from its vacant to its operative position, and a pawl and ratchet to rewind said spring by a step by step movement and means operated by said control shaft to move said ratchet.

20 5. In a taximeter, a control shaft, means normally locking said shaft against movement, weight controlled means to release said locking means, a spring, means whereby when said weight controlled means has been actuated said spring will rotate said shaft to its operative position, and means whereby when said shaft is rotated from its operative position to its vacant position said spring will be rewound by a step by step movement.

25 6. In a taximeter, a control shaft, a projection carried thereby, a switch, said projection normally closing said switch, and a stop pawl to engage said projection to prevent the shaft from

being moved too rapidly beyond its home position.

7. In a taximeter, a control shaft, a projection carried thereby, a switch, said projection normally closing said switch, a fare drum, a stop pawl, and means whereby said fare drum controls said pawl so as to hold said pawl in the path of movement of said projection until such time as said drum has been returned to its zero position.

10 8. In a taximeter, a control shaft, a lever, arms rotatably mounted on said lever, studs carried by said control shaft, weight controlled means whereby one of said arms engages one of said studs and moves said control shaft from vacant to operative position, means to hold said arms against rotation after said control shaft has been moved to its operative position, and means whereby the movement of said control shaft from its operative position to its home position will return said weight controlled means to its normal condition.

15 9. In a taximeter, a unit consisting of a plurality of arms and a ratchet, a controlled shaft, means normally holding said arms against rotation, weight controlled means whereby the holding means is released and one of said arms rotates the control shaft from its vacant to its operative position, and means controlled by said control shaft whereby said weight controlled means is returned to its initial condition as said control shaft is moved from its operative to its home position, said last-named means including said ratchet.

GROVER CLEVELAND COIL. 35
